(57) **CLAIM**

The ornamental design for a strap buckle assembly, as shown and described.

DESCRIPTION

FIG. 1 is a top plan view of the strap buckle assembly showing my design.

FIG. 2 is a side elevation view thereof, an opposite side view being identical;

FIG. 3 is an upper perspective view thereof; and,

FIG. 4 is another upper perspective view thereof, showing an extended position of the strap.

The broken lines are presented for illustrative purposes to indicate continuing length of the strap of the design.
